UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed April 21, 1923. Serial No. 633,573.

To all whom it may concern:

Be it known that I, JESSE A. B. SMITH, a citizen of the United States, residing in Stamford, in the county of Fairfield and State of Connecticut, have invented certain new and useful Improvements in Typewriting Machines, of which the following is a specification.

The invention relates to sheet-collating mechanism in typewriting machines.

In writing individual statements or ledger-sheets in a typewriting machine, a record-sheet is commonly employed, on which are accumulated the several entries made on the successive statement or ledger sheets. For convenience, the record-sheet is allowed to remain in the machine while the statement or ledger sheets are successively introduced and removed; means being provided for holding the record-sheet, ready for writing on the next blank line thereof, while the statement-sheet, or ledger-sheet, or both ledger and statement sheets are collated or positioned with respect to the printing line of the platen for writing at a given line-position thereon. In other words, the ledger-sheet, for instance, should be positioned for writing on the blank line following the last entry thereon, and such blank line should coincide with the blank line next following the last entry on the underlying record, sheet.

For easy insertion of the ledger and statement sheets, the feed-rolls are released. While the feed-rolls are released, the record-sheet, which is usually wider than the other sheets, is held at its margins to the platen by spring clips or fingers. In returning the carriage after conclusion of the previous entry, the platen will ordinarily have been automatically line-spaced; so that, at the time the following ledger or statement sheet is being positioned, the record-sheet stands ready for writing on the next blank line thereof. A collating table for the ledger and statement sheets has heretofore been provided; with pins thereon whereby to impale the ledger or statement sheet on the front of the table; the pins serving, not only as a means for aligning or squaring the sheets, but also to hold a sheet, for instance, a ledger-sheet, while a statement-sheet is positioned thereover. The record-sheet ordinarily passes behind the collating table

and is clear of the pins. The sheets collated on the table have been provided with rows of holes extending marginally lengthwise thereof to receive the pins; and the particular holes employed, in each instance, depend upon the position, lengthwise of the sheet, of the point at which writing is to be commenced.

Heretofore the diameter of the holes has been such as to cause them to be graduated apart at double line-space distance; leaving sufficient stock between the holes to prevent tearing of the paper. It is, however, sometimes desired to type at every line-space position; that is to say, to do single line-space work on the record-sheet and ledger or statement sheet. In such case, the chances are even that the required setting of the ledger-sheet with respect to the printing line of the platen will result in placement thereof over the impaling pins with the pins between two successive holes at single line-space distance from each, instead of in registry with any of the holes; thus precluding a setting of the ledger-sheet on the pins without movement of the platen. The ledger-sheet might, of course, be set up a line-space higher on the table, so as to cause holes therein to register with the pins; and, after the feed-rolls had been reapplied, and the sheet disengaged from the pins (following the collation), the platen could be turned back a single line-space, before commencing the writing, to position the proper line of the ledger-sheet at the printing line of the platen. Such back-feed of the platen would, however, return the last written line of the record-sheet to the printing line of the platen, with the result that it would be written over and obliterated by the first line of the new entry. If, on the other hand, the ledger-sheet be set down a line-space on the table and the platen subsequently given a single line-feed forward, the result will be a blank line, or break, in the writing on the record-sheet.

The object of the present invention is the provision of means whereby (instead of first falsely setting the ledger-sheet and then attempting to correct the setting by turning the platen), the pins themselves may be moved a single line-space distance to bring them into registry with pin-holes in the ledger-sheet or statement-sheet while both

the ledger and record sheets are in proper position for commencing writing.

Features of the invention are the means for carrying, guiding, and determining the proper movement of, the pins, and for simultaneously effecting such movement, of the pins at each side of the table, by means of a single finger-piece or key; this mechanism being compact and simple, and being located where it cannot foul the sheets.

The collating table is ordinarily in two sections, laterally adjustable to accommodate sheets of different widths; and a feature of the invention is the provision of operating connections for the pins, which connections remain effective whatever the adjustment of the table, and which are neither broken nor require any manipulation in making the adjustments of the table.

Other features and advantages will hereinafter appear.

In the accompanying drawings,

Figure 1 is a view, in side elevation, and partly in section, taken on the line 2—2 of Figure 2, showing a platen-frame having the paper-controlling devices of the present invention mounted thereon; the impaling pins being indicated in their upper or normal position.

Figure 2 is a view, in front elevation, of the apparatus shown in Figure 1.

Figure 3 is a view, in cross-sectional side elevation, of a part of the apparatus shown in Figure 1 showing the impaling pins as having been moved to and locked in lower position, and the actuating and locking means.

Figure 4 is a plan view, showing a ledger or individual statement sheet; the collating table and wing-scale being indicated in dotted lines behind the same.

The platen 10, by means of its axle 11, is journaled in the side plates 12 of a platen-frame. On the axle 11 are the usual hand-wheels 13 and line-space ratchet-wheel 14. The side plates of the platen-frame are connected at the rear by cross-tie 15; and, forward thereof, by rod 16. Secured to the cross-tie 15 is the usual rear paper guide and apron 17 for guiding work-pieces from the rear, down, around, and to the front of the platen. Front and rear pressure-rolls 18 and 19, respectively, are provided for holding the work-pieces to the platen, for effecting feed thereof in line-space and reverse directions upon rotation of the platen. Means, not shown, but which may be of the type found in the Underwood standard typewriting machine, are provided for throwing the pressure-rolls 18 and 19 to and from the platen, and also for throwing the apron 17 to and from the platen, to permit of easy movement of the work-sheets around the platen, for the collation thereof. The usual wing-scale 20, mounted upon the

frame of the machine, has its upper edge in close proximity to the platen, to indicate the printing line on the latter. Spring-clips, not shown, but which may be of the style found in the Underwood standard type-writing machine, are provided with rolls 21, for holding the under or record sheet to the platen, at the margins thereof, against displacement, while the pressure-rolls 18 and 19 are released.

A collating table 22, in two sections 22^a and 22^b, is mounted on a cross-bar 23, above the platen, at the front of the platen-frame. The table-sections 22^a and 22^b are adjustable with respect to each other, laterally of the machine, to accommodate work-pieces of different widths. Headed screws 24 hold the collating-table-sections to the bar 23, and slots 25 in the table-sections permit the adjustment of the table-sections when the screws 24 are loosened. The bar 23 is secured by screws 26 to brackets 27, set on the cross-rod 16. Another rod 28, mounted in brackets 29 on the side pieces 12 of the platen-frame, passes through recesses 30 in the brackets 27, and holds the latter against angular movement on the rod 16.

A work-sheet 31, which may be a ledger-sheet or a statement-sheet, is shown as having superposed thereon, between the same and the platen, a record-sheet 32. At the front of the platen, above the printing line, the statement or ledger sheet 31 is passed up, over and in front of the collating table 22. The record-sheet, on the other hand, is passed between the rolls 21 and the platen, and thence is guided rearward behind the table 22. The work-sheet 31, as shown in Figure 2, is narrow enough to pass between the rolls 21, whereas the record-sheet is sufficiently wider to be engaged by the rolls 21 and thereby directed rearwardly around the platen to its position back of the collating. When, therefore, the pressure-rolls 18 and 19 are released, the work-sheets 31 may be passed freely around the platen and onto the table 22 for collation, while the record-sheet is held against displacement by the rolls 21. It will be understood that several work-pieces 31 may be collated on the table 22. There may, for instance, be not only a ledger-sheet or an individual statement-sheet, but there may be both a ledger-sheet and an individual statement-sheet, and these sheets may be collated with respect to each other, and with respect to the record-sheet, in a manner hereinafter described.

An auxiliary table, not shown, may be provided for holding the record-sheet separated from the other sheets at the rear of the platen, so as to permit easier insertion of the ledger and individual sheets. Carbons will, of course, be inserted between the sheets; and the carbon between the record-sheet and the work-sheet next thereto may

be secured to the record-sheet by having its upper leading edge turned over the leading edge of the latter in a well-known manner. The carbons for the ledger and individual statement sheets may also be affixed to such sheets.

As shown in Figure 4, the work-sheets 31 are provided, adjacent each margin thereof, with a row of pin-holes 33. These pin-holes 10 are indicated as at double line-space distances apart. Below the space, which is provided for the heading of the work-sheets, the holes 33 have graduations in registration therewith, numbered 1, 3, 5, 7, etc. Other 15 graduations, numbered 2, 4, 6, etc., indicate single line-space distances from the next preceding hole 33. In Figure 4, the sheet is shown as positioned for writing on a line indicated by the graduation 10 between two 20 succeeding holes 33; the graduation 10 being shown as immediately above the upper edge of the wing-scale 20, which, as hereinbefore noted, denotes the printing line.

At each side of the two-part collating table 22, and projecting therethrough, and out from the front surface thereof, is a pin 34 arranged to be registered with any selected one of the holes 33 in the corresponding series, and to be passed through such 30 selected hole by pressing the work-piece to the table. The pins 34 are of a size to nicely fit the holes 33 and to hold the paper frictionally against displacement. There being a pin 34 at each side of the table, a work-sheet, 35 when impaled upon the two pins, through holes bearing the same number in the scales on the paper, will be aligned or squared with respect to the printing line and with respect to the other work-pieces. The pins, however, 40 have the further function of holding a work-piece thereon to release both hands of the operator for collating another work-piece with respect to the work-piece then on the pins.

45 The pins 34 project through vertical slots 35 in the table, and, at the rear face of the table, are fixed, each on a slide 36. The slides 36 are held to the table 22 by headed screws 37, which pass through slots 38 in the 50 slides. The movement of the slides, with the pins 34, on the table 22, is determined by engagement of the screws 37 with the ends of the slots 38. The slots are of such length as to permit the pins to be moved up and 55 down on the table a single line-space distance. The left-hand slide is shown as having an ear 39, turned rearward thereon. In the edge of this ear are two notches 40 and 41 also centered a single line-space distance 60 apart. A spring-detent 42, pinned at 43, to the rear face of the table 22, by co-operation with one or the other of the notches 40, 41, holds the slide in its upper or lower position, when the same is thrown to such position. 65 Each slide has also another ear 44,

turned rearward therefrom; and the ears 44 are bifurcated, as at 45, each loosely to engage a pin 46. Each of the pins 46 is fast to and projects laterally from an arm 47, secured by a set-screw 48 to a rock-shaft 49. 70 The rock-shaft 49 is journaled in the brackets 29 on the end plates of the carriage, and also passes through cuts 50 in the brackets 27, thereby further supporting the latter. Fast to the rock-shaft 49 is a finger-piece 51, 75 by means of which the shaft may be rocked with the arms 47 and the pins 46, to cause the slides 36 to be moved up or down. Since both the slides 36 are thus operable together from the shaft 49, only one detent-device 42 80 is necessary. It will be noted that the pins 46 are of such length as to permit lateral adjustment of the sections 22^a and 22^b of the collating table without disengagement of the pins from the ears 44 on the slides. 85

Assume that a ledger-sheet 31, when properly positioned on the platen by means of the wing-scale 20, shows one of the odd numbered graduations in registry with the printing line. In this event, the pins 34 register with one or another of the holes 33, and the sheet may be impaled upon the pins by pressing the same against the table. On the other hand, let us assume, as shown in Figure 4, that, when the sheet is in proper position, with respect to the printing line, a graduation, such, for instance, as the graduation numbered 10, registers with the printing line. In this event, as indicated in dotted lines at 34, Figure 4, the impaling pins 100 will fall between two adjacent holes 33, and the sheet cannot be impaled upon the pins by pressing the same to the table, or without disturbing the position of the sheet on the platen. In such case, the pins 34 are moved 105 from the position shown in Figure 4, until they register with the holes in the sheet next below the dotted-line positions of the pins. This movement of the pins is effected by throwing the finger-piece 51 from Figure 1 110 to Figure 3 position through the connections heretofore described. The pins being thus brought to Figure 3 position, the sheet may be impaled and held in place in the usual manner by pushing the same over the pins 115 to the table. The individual statement-sheet may then be set upon the pins in registered relation to the ledger-sheet. During this time, the record-sheet 32, as hereinbefore stated, is held in place by the rolls 21. 120 The collation, however, being completed, the pressure-rolls 18 and 19 are applied. The sheets 31 on the pins may then be pulled out to the position indicated in Figure 1, to permit line-space movement of the work-sheets, and the writing then commenced. The rounded ends of the pins 34 will cam the work-sheets off of the same, to permit of line-space movement of the sheets during the 125 writing. 130

Variations may be resorted to within the scope of the invention, and portions of the improvements may be used without others.

Having thus described my invention, I 5 claim:

1. In a typewriting machine, the combination with a revoluble platen, of a collating table, arranged at the delivery side of the platen and disposed to support the leading ends of work-sheets on the platen, sheet-holding pins carried by said table and projecting through a slot in said table from the rear thereof, positioned to enter perforations provided in the margins of a work-sheet, carried on the platen and said table, and carriers for said pins mounted at the rear of said table and adjustable thereon toward and from the platen. 10
2. In a typewriting machine, the combination with a revoluble platen, of a collating table, arranged at the delivery side of said platen and disposed to support the leading edges of work-sheets on the platen, said table comprising separate oppositely-disposed sections or body-portions, laterally adjustable with reference to each other, sheet-holding pins carried by said table and projecting forwardly through slots in said table-sections from the rear thereof, positioned to enter perforations provided in opposite lateral margins of a work-sheet carried on the platen and said table, and carriers for said pins, mounted at the rear of said table and adjustable toward and 15 from the platen. 20
3. In a typewriting machine, the combination with a revoluble platen, of a collating table, arranged at the delivery side of said platen and disposed to support the leading edges of work-sheets on the platen, said table comprising similar, independent, oppositely-disposed sections or body-portions, laterally adjustable with reference to each other, sheet-holding pins carried by said table and projecting through slots in said table-sections, from the rear thereof, positioned to enter perforations provided in the opposite lateral margins of a work-sheet carried on the platen and said table, carriers for said pins, mounted at the rear of said table and adjustable toward and from the platen, and means disposed at the rear of said table to automatically lock said carriers and pins in a plurality of adjusted 25 positions. 30
4. In a typewriting machine, the combination with a revoluble platen, of a collating table, arranged at the delivery side of said platen and disposed to support the leading edges of work-sheets on the platen, said table comprising similar, independent, oppositely-disposed sections or body-portions, laterally adjustable with reference to each other, sheet-holding pins carried by said table and projecting through slots in said table-sections, from the rear thereof, positioned to enter perforations provided in the opposite lateral margins of a work-sheet carried on the platen and said table, carriers for said pins, mounted at the rear of said table and adjustable toward and from the platen, and means disposed at the rear of said table to automatically lock said carriers and pins in a plurality of adjusted 35 positions. 40
5. In a typewriting machine, the combination with a revoluble platen, of a collating table, arranged at the delivery side of said platen and disposed to support the leading edges of work-sheets on the platen, said table comprising similar, independent, oppositely-disposed sections or body-portions, laterally adjustable with reference to each other, sheet-holding pins carried by said table and projecting through slots in said table-sections, from the rear thereof, positioned to enter perforations provided in the opposite lateral margins of a work-sheet carried on the platen and said table, carriers for said pins, mounted at the rear of said table and adjustable toward and from the platen, and means disposed at the rear of said table to automatically lock said carriers and pins in a plurality of adjusted 45 positions. 50
6. In a typewriting machine, the combination with a revoluble platen, of a collating table, arranged at the delivery side of said platen and disposed to support the leading edges of work-sheets on the platen, said table comprising similar, independent, oppositely-disposed sections or body-portions, laterally adjustable with reference to each other, sheet-holding pins carried by said table and projecting through slots in said table-sections, from the rear thereof, positioned to enter perforations provided in the opposite lateral margins of a work-sheet carried on the platen and said table, carriers for said pins, mounted at the rear of said table and adjustable toward and from the platen, and means disposed at the rear of said table to automatically lock said carriers and pins in a plurality of adjusted 55 positions. 60
7. In a typewriting machine, the combination with a revoluble platen, of a collating table, arranged at the delivery side of said platen and disposed to support the leading edges of work-sheets on the platen, said table comprising similar, independent, oppositely-disposed sections or body-portions, laterally adjustable with reference to each other, sheet-holding pins carried by said table and projecting through slots in said table-sections, from the rear thereof, positioned to enter perforations provided in the opposite lateral margins of a work-sheet carried on the platen and said table, carriers for said pins, mounted at the rear of said table and adjustable toward and from the platen, and means disposed at the rear of said table to automatically lock said carriers and pins in a plurality of adjusted 65 positions. 70

said table-sections, from the rear thereof, positioned to enter perforations provided in the opposite lateral margins of a work-sheet carried on the platen and said table, carriers for said pins, mounted at the rear of said table and adjustable toward and from the platen, and spring-controlled locking means at the rear of the table, to automatically lock said carriers and pins in a plurality of adjusted positions. 75

5. In a typewriting machine, the combination with a revoluble platen, of a collating table, arranged at the delivery side of said platen and disposed to support the leading edges of work-sheets on the platen, said table comprising similar, independent, oppositely-disposed sections or body-portions, laterally adjustable with reference to each other, sheet-holding pins carried by said table and projecting through slots in said table-sections, from the rear thereof, positioned to enter perforations provided in the opposite lateral margins of a work-sheet carried on the platen and said table, carriers for said pins, mounted at the rear of said table and adjustable toward and from the platen, and means at the rear of said table to simultaneously actuate both of said carriers to correspondingly adjust said pins. 80

6. In a typewriting machine, the combination with a revoluble platen, of a collating table, arranged at the delivery side of said platen and disposed to support the leading edges of work-sheets on the platen, said table comprising similar, independent, oppositely-disposed sections or body-portions, laterally adjustable with reference to each other, sheet-holding pins carried by said table and projecting through slots in said table-sections, from the rear thereof, positioned to enter perforations provided in the opposite lateral margins of a work-sheet carried on the platen and said table, carriers for said pins, mounted at the rear of said table and adjustable toward and from the platen, and means at the rear of said table to simultaneously actuate both of said carriers to correspondingly adjust said pins, said means being operable to effect said actuation at all positions of lateral adjustment of the table-sections with respect to each other. 100

7. In a typewriting machine, the combination with a revoluble platen, of a collating table, arranged at the delivery side of said platen and disposed to support the leading edges of work-sheets on the platen, said table comprising similar, independent, oppositely-disposed sections or body-portions, laterally adjustable with reference to each other, sheet-holding pins carried by said table and projecting through slots in said table-sections, from the rear thereof, positioned to enter perforations provided in the opposite lateral margins of a work-sheet carried on the platen and said table, carriers for said pins, mounted at the rear of said table and adjustable toward and from the platen, and means disposed at the rear of said table to automatically lock said carriers and pins in a plurality of adjusted 110 positions. 115

- the opposite lateral margins of a work-sheet carried on the platen and said table, carriers for said pins, mounted at the rear of said table and adjustable toward and from the platen, and means at the rear of said table to hold said carriers in slidable relation to said table and automatically limit the movement of said carriers and pins to one line-space distance of adjustment.
8. In a typewriting machine, the combination with a revoluble platen, of a collating table, arranged at the delivery side of said platen and disposed to support the leading edges of work-sheets on the platen, said table comprising similar, independent, oppositely-disposed sections or body-portions, laterally adjustable with reference to each other, sheet-holding pins carried by said table and projecting through slots in said table-sections from the rear thereof, positioned to enter perforations provided in the opposite lateral margins of a work-sheet carried on the platen and said table, carriers for said pins mounted at the rear of said table and adjustable toward and from the platen, and means at the rear of said table to effect said adjustment so that said pins will engage or register with the marginally-disposed perforations of the work-sheet to adjust said work-sheet to writing position.
9. In a typewriting machine, the combination with a revoluble platen, of a collating table arranged at the delivery side of the platen and disposed to support leading ends of work-sheets on the platen, said table comprising similar, independent, oppositely-disposed sections or body-portions, laterally adjustable with reference to each other, a sheet-holding pin carried by each of said oppositely-disposed table-sections and projecting through slots in said table-sections from the rear thereof, each of said pins being positioned to enter perforations provided in the opposite lateral margins of the work-sheet adjacent the respective pins, and a carrier for each of said pins mounted at the rear of each table-section and simultaneously, correspondingly, adjustable on said sections toward and from the platen.
10. In a typewriting machine, a rotary platen, means for holding a record-sheet in fixed position over the platen, means for effecting line-space movement with the platen of the record-sheet and superposed work-sheet, which latter has length-wise thereon, a plurality of pin-holes disposed at multiple line-space-distances apart, a collating table comprising similar, independent sections oppositely disposed and laterally adjustable toward and from each other, a pin projecting through a slot in each of said opposite sections of said table for impaling the superposed work-sheets through one or another of the holes in said sheets according to the desired setting of the sheets with respect to the printing line of the platen, and means at the rear of said table for simultaneously and correspondingly moving the pins lengthwise of the work-sheet holes, to effect registration thereof with said holes when the desired setting of the work-sheet would otherwise preclude the registration of the pins with any of the holes.
11. In a typewriting machine, a rotary platen, means for holding a record-sheet in fixed position over the platen, means for effecting line-space movement, with the platen, of the record-sheet and a superposed work-sheet, which latter has lengthwise thereof a row of pin-holes therein pitched at multiple line-space distance apart, a collating table for receiving the superposed work-sheet, a pin projecting through a slot in the table, from the rear thereof, for impaling the superposed work-sheet through one or another of the holes in such sheet, according to the desired setting of the sheet with respect to the printing line of the platen, and means for moving the pin lengthwise of such row of holes to effect registration thereof with one of the holes when the desired setting of the sheet would otherwise preclude registration of the pin with any of the holes.
12. In a typewriting machine, a rotary platen, means for holding a record-sheet in fixed position over the platen, means for effecting line-space movement, with the platen, of the record-sheet and a superposed work-sheet, which latter has lengthwise thereof a row of pin-holes therein pitched at multiple line-space distance apart, a collating table for receiving the superposed work-sheet, a pin projecting through a slot in the table, from the rear thereof, for impaling the superposed work-sheet through one or another of the holes in such sheet, according to the desired setting of the sheet with respect to the printing line of the platen, a carrier for the pin on the rear of the table, means for moving the carrier to effect movement of the pin along the slot lengthwise of such row of holes, whereby to bring the pin into registration with one of the holes when the desired setting of the sheet would otherwise preclude registration of the pin with any of the holes, and means for holding the carrier in the position to which it may have been moved.
13. In a typewriting machine, a rotary platen, means for holding a record-sheet in fixed position over the platen, means for effecting line-space movement, with the platen, of the record-sheet and a superposed work-sheet, which latter has lengthwise thereof a row of pin-holes therein pitched at multiple line-space distance apart, a collating table for receiving the superposed work-sheet, a pin projecting through a slot in the table, from the rear thereof, for impaling the superposed work-sheet through

- one or another of the holes in such sheet, according to the desired setting of the sheet with respect to the printing line of the platen, a carrier for the pin on the rear of the table, and means for moving the carrier to effect movement of the pin along the slot lengthwise of such row of holes, whereby to bring the pin into registration with one of the holes when the desired setting of the sheet would otherwise preclude registration of the pin with any of the holes; the last-named means comprising an arm, a pin projecting laterally from the arm for engagement with the carrier, and means for throwing the arm to move the carrier; the pin on said arm being of sufficient length to maintain engagement with the carrier in the different laterally adjusted positions of the table.
14. In a typewriting machine, a rotary platen, means for holding a record-sheet in fixed position over the platen, means for effecting line-space movement, with the platen, of the record-sheet and a superposed work-sheet, which latter has lengthwise thereof, at each side, a row of pin-holes therein pitched at multiple line-space distance apart, a collating table for receiving the superposed work-sheet, a pin at each side of the table, projecting through a slot in the table from the rear thereof, for impaling the superposed work-sheet through one or another of the holes, in each row thereof, in such sheet, according to the desired setting of the sheet with respect to the printing line of the platen, a pair of slides, each carrying one of the pins, two arms, each having a pin-and-slot engagement with one of the slides, a rock-shaft on which the arms are fast, and means for rocking the rock-shaft for simultaneously moving the pins lengthwise of such rows of holes to effect registration thereof with one of the holes, in each row, when the desired setting of the sheet would otherwise preclude registration of the pins with any of the holes.
15. In a typewriting machine, a rotary platen, means for holding a record-sheet in fixed position over the platen, means for effecting line-space movement, with the platen, of the record-sheet and a superposed work-sheet, which latter has lengthwise thereof a row of pin-holes therein pitched at multiple line-space distance apart, a collating table, adjustable laterally of the machine, for receiving the superposed work-sheet, a pin projecting through a slot in the table, from the rear thereof, for impaling the superposed work-sheet through one or another of the holes in such sheet, according to the desired setting of the sheet with respect to the printing line of the platen, a carrier for the pin on the rear of the table, and means for moving the carrier to effect movement of the pin along the slot lengthwise of such row of holes, whereby to bring the pin into registration with one of the holes when the desired setting of the sheet

would otherwise preclude registration of the pin with any of the holes; the last-named means comprising an arm, a pin projecting laterally from the arm for engagement with the carrier, and means for throwing the arm to move the carrier; the pin on said arm being of sufficient length to maintain engagement with the carrier in the different laterally adjusted positions of the table.

16. In a typewriting machine, a rotary platen, means for holding a record-sheet in fixed position over the platen, feed-rolls bearing on the platen for effecting line-space movement, with the platen, of the record-sheet and a superposed work-sheet, which latter has lengthwise thereof a row of pin-holes therein graduated at multiple line-space distance apart, a collating table for receiving the superposed work-sheet, means for releasing the feed-rolls to permit such superposed work-sheet to be passed freely around the platen and onto the front of the table while the record-sheet is held fixed and guided to the rear of the table, pins projecting through slots in the table from the rear thereof for impaling the superposed work-sheet through one or another set of the holes in such sheet, according to the desired setting of the sheet with respect to the printing line of the platen, and means for moving the pins lengthwise of such row of holes to effect registration thereof with one of the sets of holes when the desired setting of the sheet would otherwise preclude registration of the pins with any of the holes.

17. In a typewriting machine, a rotary platen, means for holding a record-sheet in fixed position over the platen, means for effecting line-space movement, with the platen, of the record-sheet and a superposed work-sheet, which latter has lengthwise thereof a series of indices graduated at multiple line-space distances apart, a collating table for receiving the superposed work-sheet on its front face, means carried on but at the rear of said table projecting upwardly through slots therein for co-operation with one or another set of said indices, for holding the superposed work-sheet thereat, according to the desired setting of the sheet with respect to the printing line of the platen, and means for slidably moving said holding means to effect registration thereof with one of said indices when the desired setting of the sheet would otherwise preclude registration of the holding means with any of said indices.

JESSE A. B. SMITH.
